UNITED STATES PATENT OFFICE.

GUS F. LENK, OF DALLAS, TEXAS, ASSIGNOR TO SUPERIOR INCINERATOR COMPANY OF TEXAS, OF DALLAS, TEXAS, A CORPORATION OF DELAWARE.

CHARGING-HOLE CLOSURE FOR INCINERATORS.

Application filed September 29, 1923. Serial No. 665,614.

To all whom it may concern:

Be it known that I, GUS F. LENK, a citizen of the United States of America, residing at Dallas, in the county of Dallas and 5 State of Texas, have invented certain new and useful Improvements in Charging-Hole Closures for Incinerators, of which the following is a specification.

This invention relates to new and useful 10 improvements in charging hole closures for incinerators.

It is customary in charging or delivering garbage and trash to incinerating furnaces to drive the vehicle over a hole in the top of 15 the combustion chamber and dump the load through the hole into said chamber. The fire directly under this hole becomes intensely hot and when the hole is not being used, it must be closed. Owing to the intense 20 heat under the hole, particularly when closed, metal covers which are exposed directly to the flames or the hot gases soon warp and break. Further such a cover becomes too hot to handle satisfactorily.

25 The object of my invention is to provide a charging hole closure wherein no metal is exposed to the flames or the direct action of the hot gases and whereby the charging hole is protected against the same.

30 A further object is to provide a metal cover for the upper end of the hole which may be handled in the usual manner and a protecting or secondary cover or tile of fire resisting material suspended therefrom 35 at the bottom of the hole and substantially closing the same, whereby the lining of the hole and the metal cover are kept comparatively cool.

Another object of the invention is to provide 40 a charging hole closure formed of a tile of fire resisting material and a metal suspending or supporting member therefor fully protected from the fire by said tile.

A construction designed to carry out the 45 invention will be hereinafter described together with other features of the invention.

The invention will be more readily understood from a reading of the following specification and by reference to the accompanying 50 drawings, in which an example of the invention is shown, and wherein:

Fig. 1 is a sectional view of one of the charging holes of an incinerator equipped with a closure constructed in accordance 55 with my invention,

Fig. 2 is a plan view of the lower cover or closure member,

Fig. 3 is a cross-sectional view on the line 3—3 of Fig. 2,

Fig. 4 is a cross-sectional view on the line 60 4—4 of Fig. 2, and

Fig. 5 is a cross-sectional view on the line 5—5 of Fig. 2.

In the drawings the numeral 10 designates the arch of the combustion chamber 65 of an incinerator or any other furnace with which the invention may be used. The furnace roof 11 is above the arch and a floor 12 is laid upon the roof. A downwardly converging circular opening 13 is formed 70 in the floor and roof and is continued through a sectional block 14 of fire resisting material which is built into the arch. An upwardly flared annular metal lining or hopper 15 is fitted in the opening and has 75 an outwardly directed flange 16 at its upper end counter-sunk in the floor 12.

A circular flat metal plate or cover 17 rests upon the flange flush with the floor. An eye bolt 18 is fastened in the cover by nuts 20 80 and affords a point of connection with means used to lift and place the closure. A pair of spaced bolts 19 hang through the cover, being fastened by nuts 21 engaging the under and upper sides of said cover.

The bolts 19 have eyes 22 at their lower ends which engage in the eyes of bolts 23 passing through an annular metal hanger 24. The hanger is made of two semi-circular sections and has depending side walls 25 and their 90 lower ends are provided with inwardly directed semi-circular flanges 26. A circular tile 27 of fire proof clay or other fire resisting material is mounted in the hanger and has a diameter larger than that of the hanger 95 so as to project beyond the same and shield it from the fire below. The diameter of the tile is such as to cause the latter to substantially close the lower end of the hopper, sufficient clearance being allowed to move 100 the tile vertically. Owing to the upward flare of the hopper the tile requires but little clearance at the bottom of the hopper. The tile, as described, projects circumferentially beyond the side walls 25 of the hanger. An enlarged annular boss 29 is formed on 105 top of the tile and an annular groove or seat 28 is provided at the intersection of the boss and the lower portion of the tile. The boss has sumps 30 for the eye bolts 23 as 110

well as side recesses 31 for the bolts 32 of splice plates 33 which unite the sections of the hanger. The tile is of course cast in one piece. The hanger sections are placed 5 around the boss 29 with the walls 25 embracing the sides of the boss and the flanges 26 seated in the grooves 28. If the tile is cracked or broken it can be readily replaced.

It will be seen that the underside of the 10 tile 27 is presented to the fire and the hanger is protected therefrom by the tile. The greater portion of the hopper is shut off from the fire and the metal cover 17 above is far enough removed to remain comparatively 15 cool. When it is desired to open the hole, suitable hoisting means (not shown) is connected with the bolt 18 and the closure elevated until the tile or lower cover is above the vehicle carrying the load to be dumped 20 through the hole. After the charge is complete the closure is lowered until the cover 17 is in place, the tile being guided into the hopper 15.

It is apparent that many methods of supporting the tile and suspending it from the cover may be carried out as well as changes 25 in the tile hanger, all such as come within the scope of appended claims are included. It is intended herein to cover the use of the 30 tile and hanger alone, irrespective of how they may be mounted in the hole.

What I claim is:

1. In a charging hole closure for furnaces,

an annular fire resisting tile having a boss 35 on its upper side and a circumferential groove, an annular split metal hanger surrounding the boss and having an inwardly directed flange engaging in the groove of the tile, splice plates connecting the parts of the hanger, the tile extending radially beyond 40 the hanger and plates and means for supporting the hanger in a charging hole.

2. In a charging hole closure for furnaces, the combination with a metal hopper, of a metal cover resting upon the upper end of 45 the hopper, supporting elements suspended from the cover in the hopper, a metal hanger attached to the lower ends of the supporting elements, and a tile of fire resisting material suspended from the hanger within the 50 lower end of the hopper, the cover and tile being removable upwardly as a unit to provide an unobstructed passage through the hopper.

3. In a charging hole closure for furnaces, 55 a cover plate, an eye on the plate, bolts depending from the plate, a split hanger having a retaining flange, means for suspending the hanger at the lower ends of the bolts, and a tile of fire resisting material surrounded by the hanger and receiving the retaining flange.

In testimony whereof I affix my signature.

GUS F. LENK.
